[57] CLAIM

The ornamental design for chair pouch, as shown and described.

DESCRIPTION

FIG. 1 is a perspective view of a chair pouch showing my new design;

FIG. 2 is a perspective view thereof; with the lockable flap shown in an open position;

FIG. 3 is a front elevational view thereof;

FIG. 4 is a right side elevational view thereof;

FIG. 5 is a rear elevational view thereof; and,

FIG. 6 is a top plan view thereof.

The broken line showing of chair is for illustrative purposes only and forms no part of the claim. The undisclosed bottom has not been claimed.
